DESIGN FOR A TOY PILOT MODEL

Genevieve S. Foster, San Diego, Calif.

Application April 27, 1948, Serial No. 145,995

Term of patent 14 years

(Cl. D34—4)

To all whom it may concern:

Be it known that I, Genevieve S. Foster, a citizen of the United States of America, residing at San Diego, in the county of San Diego and State of California, have invented a new, original, and ornamental Design for Toy Pilot Model, of which the following is a specification, reference being had to the accompanying drawings, forming a part thereof.

Fig. 1 is a perspective view of a toy pilot model, showing my new design, and Fig. 2 is a side elevational view of the toy pilot model.

I claim:

The ornamental design for a toy pilot model, substantially as shown.

GENEVIEVE S. FOSTER.
